US00D868831S

(12) United States Design Patent (10) Patent No.: US D868,831 S
Elatta (45) Date of Patent: * Dec. 3, 2019

(54) DISPLAY SCREEN OR PORTION THEREOF WITH ICON

(71) Applicant: Agile Transformation, Inc., Omaha, NE (US)

(72) Inventor: Sally Elatta, Omaha, NE (US)

(73) Assignee: Agile Transformation, Inc., Omaha, NE (US)

() Term: 15 Years

(21) Appl. No.: 29/690,124

(22) Filed: May 6, 2019

Related U.S. Application Data

(63) Continuation of application No. 29/663,964, filed on Sep. 20, 2018, now Pat. No. Des. 847,857, which is a continuation-in-part of application No. 29/626,750, filed on Nov. 20, 2017, now Pat. No. Des. 831,697, which is a continuation of application No. 29/582,748, filed on Oct. 31, 2016, now Pat. No. Des. 806,120.
